A. B. ROGNLIE

SEPARABLE RIM

Filed June 30, 1922

UNITED STATES PATENT OFFICE.

ADOLPH B. ROGNLIE, OF SHELLY, MINNESOTA.

SEPARABLE RIM.

Application filed June 30, 1922. Serial No. 571,900.

To all whom it may concern:

Be it known that I, ADOLPH B. ROGNLIE, a citizen of the United States, residing at Shelly, in the county of Norman and State of Minnesota, have invented certain new and useful Improvements in Separable Rims, of which the following is a specification.

My invention seeks to provide a separable 10 rim for vehicle wheels of such construction that while the members will be firmly held together under all normal conditions they may be easily separated when it is desired to remove a tire. The invention is illustrated 15 in the accompanying drawings and will be hereinafter fully set forth.

In the drawings—

Figures 1 and 2 are sections taken diametrically through a rim of my invention 20 and in planes at right angles to each other;

Fig. 3 is an enlarged detail perspective view of a portion of the rim showing the members separated.

The rim consists of two circular bands 25 1 and 2 each provided at one edge with a flange 3 which is adapted to bear against the inner portion of a tire so that, when the rim members are brought together, the tire will be effectually held between said flanges.

The band 1 is of somewhat greater width than the band 2, as clearly shown in Figs. 1 and 2, and will, therefore, overlap the inner edge of the latter band which is provided with a circumferential shoulder 4 30 upon its outer surface against which the edge of the band 1 may abut so that the rim members will be maintained in the proper relation to prevent cramping of the tire, while at the same time the tire will

40 be effectually held. The band 1 is provided at intervals on its inner surface with lugs 5, the length of which is disposed transversely to the band and the inner ends of the lugs are beveled, as indicated at 45 6. Adjacent the outer end of each lug, a short longitudinally disposed slot 7 is provided in the band 1 to facilitate

the separation of the bands when a tire is to be removed. The band 2 is provided

50 at its inner edge with projecting keeper tongues 8 constructed with slots 9 of the same form and dimensions as the lugs 5

so that they may engage over the said lugs. It will be readily understood that the tongues 8 correspond in number and position with the lugs 5 so that they readily mate when the bands 1 and 2 are brought together, and the tongues are resilient so that they will readily ride over the lugs and spring into engagement therewith. An 55 opening 10 for the valve stem is provided through the circular band 1 and both bands are reinforced by plates 11 secured to their inner surfaces around and adjacent the said opening so that an increased surface will be 60 presented to the valve stem and the liability of the stem being cut by the rim will be thereby minimized. 65

As shown most clearly in Figs. 1 and 2, the free edge or end of each tongue 8 will 70 lie flush with the base of the flange 3 upon the band 1. When it is desired to separate the members of the rim, therefore, it is necessary merely to insert the end of a screwdriver or other similar tool under the 75 end of the tongue 8, whereupon slight pressure exerted upon said tool will release the tongue from the outer end of the lug 5 and permit the tongue to ride over the lug if outward force be applied to the flanges 80 3. If the tongues should tend to stick through slight corrosion or other causes, the end of the screwdriver or other implement may be forced between the rim 3 and the adjacent side of the tire into and through 85 the slot 7 so as to exert a pressure against the side of the tongue directly downwardly as is evident.

My device is exceedingly simple in construction and may be produced at a low 90 cost. In assembling the rim, the two bands 1 and 2 are merely pushed together and the tongues 8 ride easily and automatically over and into engagement with the lugs 5. The shoulders 4 present a structure whereby 95 the outer circumference of the rim will be flush and smooth throughout so that there are no projections which might pinch or otherwise injure the tire.

Having thus described the invention, 100 what is claimed as new is:

A separable rim comprising circular bands adapted to fit together with their inner edges overlapping and their outer sur-

faces flush throughout their extent, the overlapping band being provided at intervals with longitudinally disposed slots, transversely disposed locking lugs on the inner circumference of said band having their outer ends disposed immediately adjacent said slots, and resilient locking tongues pro-

jecting from the inner edge of the overlapped band and provided with slots to receive said lugs.

In testimony whereof I affix my signature.

ADOLPH B. ROGNLIE. [L.S.]
